M. DESROCHERS.

HOLDER FOR PENCILS AND THE LIKE.

APPLICATION FILED JAN. 22, 1921.

1,416,799.

Patented May 23, 1922.

UNITED STATES PATENT OFFICE.

MAXIMILIAN DESROCHERS, OF MONTREAL, QUEBEC, CANADA.

HOLDER FOR PENCILS AND THE LIKE.

1,416,799.

Specification of Letters Patent. Patented May 23, 1922.

Application filed January 22, 1921. Serial No. 439,198.

To all whom it may concern:

Be it known that I, MAXIMILIAN DESROCHERS, a subject of the King of Great Britain, and resident of the city of Montreal, 5 in the Province of Quebec and Dominion of Canada, have invented certain new and useful Improvements in Holders for Pencils and the like, of which the following is a full, clear, and exact description.

10 This invention relates to improvements in holders for pencils and the like and is particularly adapted for attachment to a typewriting machine.

At the present time, the typewriter desks 15 in general use are of the drop head type and include a swinging table to which the typewriter is secured. In closing the desk, the swinging table assumes an inclined position and pencils, erasers or other small articles 20 lying thereon slide to the back and either fall off or become hidden among papers which may be on the table behind the typewriter.

According to the present invention, the 25 holder consists of a small box or receptacle provided with spring clips by means of which it may be attached to the frame of the typewriter without the use of tools and in such a manner as not to interfere with the 30 operation of the machine. The box is preferably of such a construction that it will remain open or closed without the use of any supplementary fastening means.

In the drawings which illustrate the invention;—

Fig. 1 is a rear elevation of a holder according to this invention.

Fig. 2 is a plan view of the holder in open position.

40 Fig. 3 is an end elevation of the holder open and illustrating the method of attachment to a machine.

Fig. 4 is an end elevation of the holder closed.

45 Referring more particularly to the drawings, 11 and 12 designate the two parts of the holder which for convenience may be described as the body and cover respectively. The body 11 comprises a substantially flat

50 plate 13 which may if desired be provided at its upper edge with a rearwardly projecting flange 14 and which is slightly forwardly curved in its lower portion 15. The body is provided with a pair of lugs or tongues 16 55 preferably cut and stamped up from the material of the body and serving to releas-

ably connect to the body a spring clip 17 adapted to attach the device to the frame of a typewriter. This clip is designed to be forced over the frame 18 of a typewriter and 60 includes converging portions 19, which will grip the frame, as clearly shown in Figures 3 and 4, and hold the device against falling off the frame. The particular shape of the clip is of small importance as it will of necessity be of different shapes for different makes of typewriting machines. At the ends of the body member 11, forwardly projecting end plates 20 are provided which are for the most part circularly curved in periphery but 70 which adjoin the plate 13 at a straight line tangent to the circle, as shown at 21. The upper part 22 of the periphery of each end plate is also tangent to the circular part of the periphery and meets the tangential portion 21 at an acute angle at the upper edge of the plate. The forwardly curved lower edge of the plate follows the curvature of the ends to a point substantially under the centres of the ends, as clearly shown in Figures 3 and 4.

The cover portion 12 is of substantially the same form as the body portion, except that the front 23 curves under for a considerably greater distance than in the back portion 85 to form a bottom 24 which fits inside the curved portion 15 of the body. The cover is provided with ends 25 of the same shape as the body ends and connected thereto by pivots 26 disposed concentrically with respect to the curved peripheries of the ends. The upper edge of the cover portion is provided with an outwardly projecting flange 27 which may serve as a handle to facilitate opening and closing the box. The curved 90 portion or bottom 24 of the cover is provided with an outwardly projecting lug 28 adapted to abut the lower edge of the body and form a stop limiting the opening of the device. In the same way, the body is provided with 100 one or more inward projections 29 adapted to engage the edge of the cover to assist the stop 28 in limiting the outward movement. In order to hold the device in closed position, the ends of one member, for example, 105 the cover, are provided with outwardly facing recesses 30 and the ends of the other member, for example the body, are provided with corrugations 31 forming inward projections disposed to enter the depressions 30 110 when the box is closed. The depressions on one member in riding over the other member

to reach the recesses 30 produce a slight flexure of the end members, which is relieved when the projections drop into the recesses. The parts are thus releasably held in closed 5 position by the resiliency of the ends.

The operation of the device is extremely simple. It is attached to a typewriter frame by hooking the upper fingers 19 over the frame and swinging the lower fingers under 10 the frame, the lower fingers being flexed in the movement and resuming substantially their normal position to hold the device to the typewriter. The flange 14 of the body overlies the small space between the body 15 and typewriter frame and serves to keep small bodies from falling into this space. To open the box, the flange 27 of the cover is grasped and moved outwardly and downwardly in a circular direction until movement is checked by the stops 28 and 29. In 20 this form the device is small and compact, projecting only a short distance beyond the typewriter frame, and is not at all in the way of the operator, especially as the holder 25 is usually attached to the bottom end member of the frame. The bottom of the holder being circularly curved, there are no corners or crevices in which a pencil or eraser can lodge, so that the same may be very easily 30 extracted by inserting the fingers and sliding the pencil or eraser up along the surface. When the typewriter desk is to be closed, the 35 opening movement is reversed and, when fully closed, the parts 30 and 31 hold the device against accidental opening.

Having thus described my invention, what I claim is:—

1. A device of the class described comprising a pair of parts each having a circularly 40 curved wall, said parts being pivoted together to hold the curved walls in sliding relation to one another, stops engageable with the edges of said curved walls to limit the movement of the parts, and a clip carried by one of the parts adapted to attach 45 the receptacle to a typewriter frame.

2. A device of the class described comprising a pair of parts forming between them a receptacle having a surface curved bottom, said parts being pivotally related to 50 permit opening and closing of the receptacle, means for attaching the receptacle to a typewriter or the like, and means for releasably holding the receptacle in closed 55 position.

3. A device of the class described, comprising a body member and a cover member, each 60 of said members including a plate, and end members connected thereto having substantially circular peripheries, said plates being

curved in part to the curvature of the end peripheries, and pivots disposed concentrically of the peripheries of said ends connecting the body and cover members together.

4. In combination with a device according to claim 3, a spring clip carried by one of the members adapted to attach the receptacle to a typewriter frame or the like.

5. In combination with a device according to claim 3, a clip carried by one of the members for attaching the receptacle to a typewriter frame or the like, a flange carried by said member adapted to span the space between the receptacle and the frame to which it is attached, and a flange carried by the other member serving as a handle to open and close the receptacle.

6. In combination with a device according to claim 3, a projection on one of the members adapted to engage the edge of the other member to limit opening movement of the members.

7. In combination with a device according to claim 3, interengageable means on the 85 ends of said members for releasably locking the members in predetermined position.

8. In combination with a device according to claim 3, tongues struck up from one of the members and disposed in spaced parallel relation therewith, and a spring clip caught between said tongues and the member adapted to releasably attach the device to a typewriter frame.

9. A device of the class described comprising a pair of members each circularly surface curved and pivotally connected for movement about the axis of their curvature, and a tangential extension from each member adapted in one position to meet at an acute angle and form a closure for the receptacle and in another position to form substantially parallel sides and end members connecting the parts together.

10. A device of the character described, comprising a receptacle provided with spaced bearings, a spring clip for attaching the receptacle to a support, said clip comprising a single length of wire having its ends passing through said bearings and directed angularly to form one side of a clamp and its intermediate portion offset to oppose said gripping members and thereby form the opposite side of the clamp, the two sides of the clamp being adapted to yieldably grip a supporting member therebetween.

In witness whereof, I have hereunto set my hand.

MAXIMILIAN DESROCHERS.
